TRACK SWITCH SYMBOL

Herbert F. Obergfell, River Forest, Ill., assignor
to Associated Electric Laboratories, Inc., Chi-
cago, Ill., a corporation of Delaware

Application May 29, 1936, Serial No. 82,411

5 Claims. (Cl. 177—311)

This invention relates in general to animated dispatcher's display panels for use in centralized traffic controlling systems for railroads, but more particularly to a combined key and lamp signal on such a display panel. This combined key and lamp signal is intended for use in a centralized traffic controlling system for railroads such as shown and described in the John Wicks application, Serial No. 82,508, filed May 29, 1936.

10 The object of the invention is the provision of a new and improved combination key and lamp signal which is manually rotated by the dispatcher to either one of its two positions and which is transparent so as to show different colors in accordance with the position of the distant track switch it corresponds to.

One of the features relates to the construction of the combined key and lamp signal to enable easy assemblage and replacement of the parts.

20 Other features of the invention will be apparent from the following description of the drawings.

Fig. 1 shows a portion of a dispatcher's animated display panel;

Fig. 2 shows the rotatable cam of the combined key and lamp signal;

Fig. 3 shows a cross section of the entire combined key and lamp signal assembled on the dispatcher's panel;

30 Figs. 4A to 4L, inclusive, show a portion of the detail parts of the combined key and lamp signal in positions corresponding somewhat to their order of assemblage. These figures taken as a whole may be considered a so-called exploded view of these detail parts.

35 Referring now to that portion of the dispatcher's display panel shown in Fig. 1, the different colored lines thereon represent corresponding railroad track sections associated with a distant field station. In each colored line is a circular glass symbol behind which the track pilot lamps 8TPL, 8TPL, 1TPL, and 1TPL are located. These lamps when illuminated indicate to the dispatcher that a train is in the corresponding track section. 8MSL and 8SSL are the dispatcher's symbol

40 signals corresponding to the main track signal and siding signal for governing train traffic from left to right. The key 8 is provided for controlling the distant track signals corresponding to the symbol signals 8MSL and 8SSL in the panel. 1SL and 1SL are dispatcher's symbol signals corresponding to the distant track signals for governing train traffic from right to left. Keys 7 and 6 are provided for controlling the distant track signals corresponding to the symbol signals 1SL and 1SL, respectively. Key 8 is a

combined key and lamp signal corresponding to a distant track switch. This combined key and symbol is manually rotatable by the dispatcher to simulate the "siding" or "main track" positions of the distant corresponding track switch. 5 The raised oblong transparent portion 8SL provides the means by which this symbol is manually rotated by the dispatcher. A green lamp G and a red lamp R are mounted directly behind the raised transparent portion 8SL to cause 8SL 10 to be illuminated green or red dependent on whether the green or the red lamp is illuminated. The green lamp G is illuminated in case the corresponding distant track switch is in "main track" position and the red lamp R is illuminated 15 in case the track switch is in its "siding" position. In case the symbol 8SL in the position shown in Fig. 1 glows red, the dispatcher knows that the corresponding distant track switch is in its "siding" position and accordingly rotates 8SL in the 20 direction indicated by the arrow to its siding position. The dispatcher also manually rotates 8SL whenever it is desired to remotely control the operation of the distant track switch.

Referring now to the details of this combined 25 key and lamp signal shown in Figs. 4A to 4L, inclusive, and in Figs. 2 and 3:

Fig. 4A shows a molded glass disc 38 having a raised portion 8SL on top and a ridge 40 on the bottom parallel with 8SL. The flat top surface 38 is glazed black, as shown in Fig. 1, while the raised portion 8SL is not glazed but is left transparent. The disc 38 fits into the flanged portion 42 of sleeve 31 shown in Fig. 4B. The ridge 40 of disc 38 fits in the cut-out portion 41 of the sleeve 31 and the upper edge of flange 42 is then spun over the edge of disc 38 to lock the two together, as shown in Fig. 3. Due to the ridge 40 in the cut-out portion 41 the sleeve 31 is rotatable with the disc 38 and raised portion 8SL. This assemblage of disc 38 and sleeve 31 is inserted from the front of the dispatcher's panel and is easily removable to permit changing of lamps in case one or both should burn out.

45 The elongated sleeve 33 shown in Fig. 4C has a flange 43 which is mounted in a hole on the panel 25 approximately flush with the front surface of the panel. The cut-out portions 44 are provided to allow clearance for the glass ridge 40 and to assist in rotating sleeve 33 with sleeve 31 and disc 38. The sleeve 33 has two cut-out portions 45 to allow clearance for the lamp jack springs 26 and 27. Sleeve 33 has a hole 33' through which the screws 36 extend to fasten the flanged collar 34 to sleeve 33 by means of the threaded nuts 35.

A projection or tongue 33' is cut in the side of sleeve 33 and bent inward so as to fit in groove 31' of sleeve 31 when sleeve 31 is slid into sleeve 33. The tongue 33' in groove 31' permits longitudinal removal and replacement of sleeve 31 but causes sleeve 33 to be rotated whenever sleeve 31 is rotated.

The sleeve 33 is rotatable in the flanged collar 32 shown in Fig. 4D. Collar 32 has a flange 46 which fits against the back of panel 25 and has holes 47 for fastening collar 32 to the panel 25 by means of screws 29 as shown in Fig. 3. Projections 48 on the lower portion of collar 32 extend in the cut-out portions 80 of fibre cam 20 shown in Fig. 4E. Projections 48 in conjunction with the inwardly extending extensions 50 of cam 20 provide stops for limiting the rotation of cam 20 and also 8SL. Fibre cam 20 is mounted on top of flange 54 of the collar 34 by means of the flat-headed screws 49 extending through the counter-sunk holes 51 of cam 20 into the tapped holes 52 of flange 54. Cam 20 has a projection 21 for operating circuit closing springs 177 and depressions 22 and 25a in which the roller detent 24 is positioned when the combined key and lamp signal is in either one of its operated positions as shown in Fig. 2. Cam 20 and collar 34 are now mounted on the bottom portion of sleeve 33 which projects below collar 32 with the holes 53 and 53' in alignment. Screws 56 extending through holes 53 and 53' screw into the nuts 55 to securely fasten sleeve 33 and the collar 34 together. The cam 20 and collar 34 rotate with sleeve 33 while the projections 48 on stationary collar 32 stop further rotation when such projections abut the inward extensions 50 of cam 20.

From the foregoing description it will be seen that the disc 30, sleeves 31 and 33, the cam 20 and the collar 34 rotate as a unit in the collar 32 which is fastened to the panel 25 when the dispatcher grasps and rotates the raised transparent portion 8SL.

Semi-circular clamps 35 and 59, shown in Figs. 4H and 4J, are clamped around the stationary collar 32 and secured in place by machine screws (not shown) extending through holes 57 to the threaded holes 58. Clamp 59 has downwardly extending arms 61 bent at 62 to form bottom portions 63 and 64. Arms 61 have side portions 60 bent at right angles thereto to stiffen or reinforce arms 61. The bottom portion 64 is provided with tapped holes 65 to permit mounting of the lamp jack springs 26, 27, and 28 by means of screws 76 as shown in Fig. 3.

55 The brackets 71 and 70, shown in Figs. 4K and 4L, are mounted on opposite sides of bottom portions 63-64 by means of machine screws extending through holes 68 to tapped holes 73. Bracket 70 is provided with tapped holes 67 for mounting circuit closing springs 177 by means of screws 71 as shown in Fig. 3. In a similar manner bracket 71 is provided with tapped holes 72 for mounting detent spring 23 by means of screws 75 as shown in Fig. 3.

65 When the dispatcher desires to operate the distant track signal corresponding to the combined key and lamp signal, he will grasp the raised transparent portion 8SL and rotate the same in the direction of the arrow shown in Fig. 1. The 70 raised transparent portion 8SL is moved into alignment with the slanting siding line on the panel, the springs 177 are closed by projection 21 and the roller detent 24 is in depression 25a. The closure of springs 177 close circuits to cause the 75 operation of the distant track switch to its "sid-

ing" position as described in the previously mentioned Wicks application.

The circuits for illuminating the green and red lamps G and R in Fig. 3 terminate on the lower ends of jack springs 26, 27, and 28.

From the foregoing description it can be seen that the various parts may be easily assembled and replaced in their proper locations. The disc 30 and sleeve 31 are removable as a unit from the front of the panel to permit replacement of lamps, the entire spring and bracket assembly is easily removable by removing the clamps 35 and 59, while the cam 20 and collar 34 may be removed by removing the screws 56 extending through holes 53 and 53' in the collar 34 and sleeve 33.

Having described the invention and what is considered to be new and is desired to be protected by Letters Patent will be set forth in the following claims.

What is claimed is:

1. In a dispatcher's animated display board panel, a combined key and lamp signal, a flanged collar for mounting said signal on said panel, rotating means in said signal comprising a disc, a first sleeve and a second sleeve, means for securely locking said disc to said first sleeve, a raised transparent portion on said disc to enable manual rotation of said rotating means, a slot in said first sleeve and a tongue in said second sleeve for permitting longitudinal separation of said sleeves and for causing both sleeves to rotate together when said raised transparent portion is rotated, a cam mounted on said second sleeve and rotated therewith, circuit closing means controlled by said cam, lamps for illuminating said raised transparent portion, a clamp mounted on said collar, and lamp jack springs mounted on said clamp for mounting said lamps.

2. In a dispatcher's animated display board panel, a combined key and lamp signal, a flanged collar for mounting said signal on said panel, rotating means in said signal comprising a disc, a first sleeve and a second sleeve, means for securely locking said disc to said first sleeve, a raised transparent portion on said disc to enable manual rotation of said rotating means, a slot in said first sleeve and a tongue in said second sleeve for permitting longitudinal separation of said sleeves and for causing both sleeves to rotate together when said raised transparent portion is rotated, a cam mounted on said second sleeve and rotated therewith, circuit closing means controlled by said cam, projections on said collar, and extensions on said cam cooperating with said projections to limit the extent of manual rotation of said rotating means.

3. In a dispatcher's animated display board panel, a combined key and lamp signal, a flanged collar for mounting said signal on said panel, rotating means in said signal comprising a disc, a first sleeve and a second sleeve, means for securely locking said disc to said first sleeve, a raised transparent portion on said disc to enable manual rotation of said rotating means, a slot in said first sleeve and a tongue in said second sleeve for permitting longitudinal separation of said sleeve and for causing both sleeves to rotate together when said raised transparent portion is rotated, a cam mounted on said second sleeve and rotated therewith, circuit closing means controlled by said cam, lamps for illuminating said raised transparent portion, a clamp mounted on said collar, lamp jack springs mounted on said clamp for mounting said lamps, and a bracket

mounted on said clamp for mounting said circuit closing means.

4. In a dispatcher's animated display board panel, a combined key and lamp signal, a flanged collar for mounting said signal on said panel, rotating means in said signal comprising a disc, a first sleeve and a second sleeve, means for securely locking said disc to said first sleeve, a raised transparent portion on said disc to enable manual rotation of said rotating means, a slot in said first sleeve and a tongue in said second sleeve for permitting longitudinal separation of said sleeves and for causing both sleeves to rotate together when said raised transparent portion is rotated, a cam mounted on said second sleeve and rotated therewith, circuit closing means controlled by said cam, depressions in said cam, and a detent roller and spring assembly for engaging said depressions to hold said rotating means in its last operated position.
5. In a dispatcher's animated display board

panel, a combined key and lamp signal, a flanged collar for mounting said signal on said panel, rotating means in said signal comprising a disc, a first sleeve and a second sleeve, means for securely locking said disc to said first sleeve, a raised transparent portion on said disc to enable manual rotation of said rotating means, a slot in said first sleeve and a tongue in said second sleeve for permitting longitudinal separation of said sleeves and for causing both sleeves to rotate together when said raised transparent portion is rotated, a cam mounted on said second sleeve and rotated therewith, circuit closing means controlled by said cam, depressions in said cam, a detent roller and spring assembly for engaging said depression to hold said rotating means in its last operated position, and a bracket mounted on said clamp for mounting said detent spring.

HERBERT F. OBERGFELL. 20
